A. H. Hart

UNITED STATES PATENT OFFICE.

ALEXANDER H. HART, OF STOCKBRIDGE, WISCONSIN.

IMPROVEMENT IN CHURNS.

Specification forming part of Letters Patent No. **39,650**, dated August 25, 1863.

To all whom it may concern:

Be it known that I, ALEXANDER H. HART, of Stockbridge, Calumet county, and State of Wisconsin, have invented a new and Improved Mode of Operating Dashers in Churns; and I do hereby declare that the following is a full and exact description thereof, reference being had to the accompanying drawings, and to the letters of reference marked thereon.

The nature of my invention consists in providing an upright conical-formed box as a churn with two paddles connected by a suitable apparatus to a lever, so that each upward or downward motion of the lever will give the paddles or dashers an opposing vibratory motion, whereby they will be on a right line with and pass each other at a point when each has traveled one half its allotted distance, thereby as the lever is worked up and down producing a violent agitation of the cream.

To enable others skilled in the art to make and use my invention, I will proceed to describe its construction and operation.

I construct a box, A, Fig. 1, with a bottom, B, that is nearly or quite equilateral with two of its opposite sides at right angles with the bottom and extending above the top of the box in a conical form, and the remaining two sides inclining inward about twelve degrees. I construct a bar, C, provided with pins *d d*, set in an opening in the cover, to which are hung the paddles *ee*, and with mortises *ff* to receive the

arms of the slide *g*. The bar is placed in the center of the top of the churn, between and parallel with the perpendicular sides thereof. The slide *g* is provided with two arms extending up perpendicular, and to which arms is connected the lever *h*, and with dovetail-formed grooves *ii* on each side of its square part, each groove running in an opposite diagonal direction on the respective sides. The paddles *ee* are each provided with a pin, *j*, with a head properly formed to work in the grooves *ii*, which is attached thereto at such a point that when the lever *h* gives the slide *g* its up-and-down motion, they (the pin *j*, there being one attached to each arm of the respective paddles) will work in the diagonally-placed grooves *ii*, thereby giving the paddles their vibratory motion, each in a reciprocally opposite direction and causing the agitation of the cream, and the consequent results therefrom of producing butter with expedition and ease.

What I claim as my invention, and desire to secure by Letters Patent, is—

The slide *g*, provided with the oblique grooves *ii*, and operated by the lever *h*, in combination with the dashers *EE*, the whole constructed, arranged, and operating in the manner and for the purposes herein set forth.

A. H. HART.
